CLAIM

The ornamental design for a square flame burner with wheels, as shown and described.

DESCRIPTION

FIG. 1 is a perspective view of a square flame burner with wheels having a front door with a door knob and the front door is in a closed position;

FIG. 2 is a perspective view of a square flame burner with wheels having a front door with a door knob and the front door is in an opened position;

FIG. 3 is a perspective view of an alternative square flame burner with wheels having a side door in a closed position instead of a front door with a knob;

FIG. 4 is a perspective view of an alternative square flame burner with wheels having a side door in a popped out position instead of a front door with a knob;

FIG. 5 is a front view of a square flame burner with wheels having a front door with a door knob;

FIG. 6 is a first side view of a square flame burner with wheels having a front door with a door knob;

FIG. 7 is a rear view of a square flame burner with wheels having either a front door with a door knob or a side door;

FIG. 8 is a second side view of a square flame burner with wheels having a front door with a door knob;

FIG. 9 is a top view of a square flame burner with wheels having either a front door with a door knob or a side door; and,

FIG. 10 is a bottom view of a square flame burner with wheels having either a front door with a door knob or a side door.
